Primary Examiner — Jennifer L Rempfer*Assistant Examiner* — Edward P Jones(74) *Attorney, Agent, or Firm* — Millen, White, Zelano & Branigan P.C.; Ryan R. Pool(57) **CLAIM**

The ornamental design for a dental wireless scanner handle as shown and described.

DESCRIPTION

FIG. 1 is a top perspective view of the dental wireless scanner handle showing my new design.

FIG. 2 is a front view thereof.

FIG. 3 is a back view thereof.

FIG. 4 is a side view thereof.

FIG. 5 is another side view thereof.

FIG. 6 is a top view thereof; and,

FIG. 7 is a bottom view thereof.

The broken lines in the drawings illustrate portions of the dental wireless scanner handle which form no part of the claimed design.

1 Claim, 7 Drawing Sheets(56)
